UNITED STATES PATENT OFFICE.

IRA L. FRENCH, OF CHICAGO, ILLINOIS, ASSIGNOR TO THE BRUMBAUGH SYSTEM, A CORPORATION OF ILLINOIS.

DESIGN FOR A DISPLAY-PILLAR.

53,121.

Specification for Design.

Patented Mar. 25, 1919.

Application filed December 3, 1918. Serial No. 265,182. Term of patent 14 years.

To all whom it may concern:

Be it known that I, IRA L. FRENCH, a citizen of the United States, residing at Chicago, in the county of Cook and State of Illinois, have invented a new, original, and ornamental Design for Display-Pillars, of which the following is a specification, reference being had to the accompanying drawing, forming part thereof.

The figure is a perspective view of a pillar, showing my new design.

I claim:

The ornamental design for a display pillar, as shown.

IRA L. FRENCH.
